UNITED STATES PATENT OFFICE.

JOSIAH C. GOODING, OF COVINGTON, INDIANA.

DESIGN FOR A DESK AND SEAT.

SPECIFICATION forming part of Design No. 24,600, dated August 20, 1895.

Application filed July 17, 1895. Serial No. 556,294. Term of patent 14 years.

To all whom it may concern:

Be it known that I, JOSIAH C. GOODING, a citizen of the United States, residing at Covington, in the county of Fountain and State 5 of Indiana, have invented and produced a new and original Design for a Desk and Seat, of which the following is a specification, reference being had to the accompanying drawings, in which—

10 Figure 1 is a view in perspective of a desk and seat embodying my design. Fig. 2 is a side view.

15 The leading features of my design consist in a raised side panel set into a curved supporting-frame, a flat horizontally-arranged top piece joining or intersecting an inclined front piece in a curve, and a seat intersecting the front piece at or near the lower edge thereof at right angles, substantially as will 20 hereinafter appear.

25 In the accompanying drawings, A represents the desk and seat as a whole. The said desk comprises a supporting-frame 1, the upper member 2 of which being straight and horizontally arranged, while the vertically-disposed members 3 and 4 join or intersect the said upper member in curves, as shown at 5. The said member 3 is set inwardly or curved for its whole length, and terminates at 30 the lower end with a projection or foot 6, while the said member 4 is approximately straight for its length and inclines slightly in the direction of the member 3, and likewise terminates at its lower end in a similar projection or foot 6. Set into this frame and extending for about the full upper half of the

same is a panel B, which, as shown, projects or bulges outward from the frame to a slight extent, and this panel is preferably of smooth surface. As shown, the panel is stamped with 40 curved figures, which are formed by cutting through the body of metal or material of which the panel is formed.

Viewing the desk and seat in the perspective shown at Fig. 1, the top piece 8 is flat 45 and horizontally disposed, while the front piece 8^a is slightly inclined in conformity with the inclination of the member 4 of the frame, and said top piece and front piece intersect or join in a curve, as indicated at 10; 50 also, as viewed from this same figure of the drawings, the said top piece and front piece are set inward somewhat from the outer edge of the frame.

The seat is bounded by the lines 11, 12, 13, 55 and 14, the line 11 intersecting the lower edge of the front piece, as shown. Also intersecting the under side of the seat and the said member 4 of the frame is a bracket 15, being inclined both with respect to said seat and 60 said member. As seen in Fig. 2, said bracket extends for a considerable portion of the width of the seat.

What I claim is—

The design for a desk and seat substantially 65 as described and shown.

In testimony whereof I affix my signature in presence of two witnesses.

JOSIAH C. GOODING.
